UNITED STATES PATENT OFFICE.

RAYMOND N. EHRHART, OF PITTSBURG, PENNSYLVANIA, ASSIGNOR TO THE WESTINGHOUSE MACHINE COMPANY, A CORPORATION OF PENNSYLVANIA.

FLUID TRANSLATION DEVICE.

No. 927,515.

Specification of Letters Patent.

Patented July 13, 1909.

Application filed April 21, 1905. Serial No. 256,749.

To all whom it may concern:

Be it known that I, RAYMOND N. EHRHART, a citizen of the United States, and a resident of Pittsburg, in the county of Allegheny and State of Pennsylvania, have invented a new and useful Improvement in Fluid Translation Devices, of which the following is a specification.

This invention relates to fluid translation devices and more particularly to the blades and vanes of such devices.

The improvements comprised in this invention are applicable to various types of fluid pressure turbines, compressors or blowers and in fact, are not limited to any particular form of such machines.

It is the object of this invention to produce a blade or vane construction whereby the blades or vanes, which may be formed in any desired manner, may be assembled compactly, cheaply and quickly.

A further object is to produce a blade construction and a method of mounting the same, adapted to overcome the tendencies of the blades to be radially dislodged when subjected to centrifugal force.

A still further object is to produce a blade and vane construction, and a method of securing the same to the mounting member, such that the blades or vanes may be readily removed, if desired, without being distorted or injured.

These and other objects I attain in blades or vanes embodying the features herein described, illustrated and set forth.

In the drawings accompanying this application and forming a part thereof, Figure 1 is a fragmentary elevation of a compressor showing a portion of the blades mounted to the rotor and a portion of the vanes mounted to the stator. Fig. 2 is a partial longitudinal section through the shaft of a compressor, showing the arrangement of the blades and vanes and the method of mounting the same to the rotor and the stator, respectively. Fig. 3 shows a partial isometric projection of the different elements forming the blade mounting piece of the rotor. Figs. 4, 5 and 6 show isometric projections of different forms of blades or vanes. Fig. 7 is an isometric projection of a spacing piece shown in connection with the end portion of two blades or vanes in Fig. 8. Fig. 8 is a perspective view of the ends of two blades illustrating the method of spacing the blades or vanes.

The blades or vanes may be stamped, pressed, drawn or extruded and are provided with a mounting end, which is cut and crimped, as shown in the Figs. 4, 5, and 6. The mounting end is provided with a suitably located hole 11. The blades and vanes may be also shaped during the operation of the pressing or stamping, the working portion being given any desired contour and the mounting portion formed with the ridges or grooves 12.

The rotor and stator, as shown in Fig. 2, are each arranged to accommodate two rows of blades or vanes, (any number of rows however may be utilized), and the operation of mounting the vanes to the stator is substantially the same as mounting the blades to the rotor.

The rotor 13 is provided with an enlarged portion 14, with suitably tapped holes 15 and 16 at either side for mounting the blades and attaching the anchoring or holding rings 18 and 19. The holding ring 19 is provided with suitably arranged holes 20, conforming in location and size with the holes 15 of the rotor portion. Mounting screws 21 are inserted through the holes 20 and screwed into the tapped holes 15 in the operation of mounting one row of blades and the holding ring 19. Annular ridges 22, of the holding ring 19, interleave with annular grooves 23 of the rotor portion 14.

The holding ring 18 is provided with the holes 20 and annular grooves 24, with which suitably arranged annular ridges 25, of the portion 14, interleave.

In mounting the blades to the rotor, the grooves or ridges 12, with which the base portions are provided, are made to interleave with the grooves or ridges 23 or 25 and the holes 11 are made to coincide with the holes 15 or 16 as the case may be, of the enlarged portion 14 of the rotor. After the blades are in place, the holding rings 18 and 19 are secured to the rotor by the screws 21 and since they are equipped with the grooves 24 and ridges 22 respectively, each of the blades composing the two rows will be rigidly held in place.

As a further means of insuring a rigid mounting of the blades, the end portion 10 is bent against the internal face of the mounting piece, as shown.

The stator is provided with an annular lug 26 to which the holding pieces 28 and 29

are connected by the screws 30. The vanes, like the blades, are equipped with ridges or grooves 12, which interleave with suitably arranged grooves and ridges on the individual mounting pieces.

5 The portion 25 is deemed unnecessary in the vanes as they are not subjected to the dislodging forces that the blades encounter.

10 A lug 31 is shown in Figs. 4, 5, and 6 attached near the outer end of the blade; after the blades are mounted the portion 31, of one blade, fits into a slightly depressed portion with which the adjacent blade is provided. Under these conditions the ends 15 of the separate blades are rigidly held in place and prevented from any relative motion.

15 A modified form of the spacing piece is shown in Fig. 7. The piece consists of a 20 spool portion 32 provided with end lugs 33, which are adapted to fit into holes 34 near the outer portion of the blades or vanes as shown in Fig. 8. After the blades or vanes are mounted to the rotor or stator, the working 25 portions are turned to occupy predetermined positions. The grooves or ridges 12 in the mounting portion of the blades or vanes may be formed by the pressure of the holding or anchoring rings against their 30 mounting portions.

It is obvious that the blades or vanes may be readily removed from their respective 35 holding members without being distorted or injured and that no opportunity is given for the blades to be radially dislodged when subjected to centrifugal force.

Although I have described but one embodiment of my invention, other forms and details of construction may readily suggest 40 themselves to one skilled in the art and still fall within the spirit and scope of my invention and I further desire it to be understood that I do not limit the application of my invention to rotary compressors.

45 Having thus described my invention, what I claim and desire to secure by Letters Patent is:

1. In combination with a rotor or a stator, a blade or vane holding element composed 50 of serrated mounting pieces and oppositely serrated holding pieces adapted to secure the blades or vanes to said rotor or stator.

2. In combination with a blade or vane holding element, an annular row of blades or 55 spacing piece between adjacent blades and means formed integrally with the said piece and extending into said blades for securing said piece in place.

3. In combination with a blade or vane holding element, an annular row of perforated blades, a spacing piece between adjacent blades and means formed integrally with said piece and coöoperating with the blade perforations for securing said piece in 60 place.

4. In combination with a blade or vane holding element, composed of serrated mounting pieces and oppositely serrated holding rings, a blade or vane composed of a working portion and a serrated mounting portion and means dependent on the serrations and said holding ring for mounting the 70 said blade or vane to the said mounting element.

5. In combination with a blade holding element, composed of a mounting piece and oppositely formed holding pieces adapted to be secured to said mounting piece by screws or bolts, a blade composed of a working portion and a mounting portion provided with 75 a mounting hole, and means dependent on the holding ring for securing the said blade to the said mounting piece, such that said bolt or screw is inserted through said mounting hole.

85 6. In combination with a blade holding element, composed of a serrated mounting piece and oppositely formed serrated holding pieces adapted to be secured to said mounting piece by screws or bolts, a blade or vane composed of a working portion and a serrated mounting portion provided with a mounting hole, and means dependent on the holding ring for securing the said blade or vane to the said mounting piece, such that said bolt or screw is inserted through said mounting hole.

90 7. In combination with a blade holding element, composed of a serrated mounting piece and oppositely serrated holding piece 100 adapted to be secured to the said mounting pieces, a blade or vane provided with a laterally extending or bent-over portion and means for securing the said blade or vane to said mounting element such that the said 105 laterally extending portion shall fit against the face of said mounting element.

8. In combination with a blade or vane holding element, comprising a serrated mounting piece and an oppositely serrated holding piece, a blade or vane composed of a working portion and a serrated mounting portion, and means for securing said ring to 110 said mounting piece and for mounting said blade or vane on said rotor or stator.

115 9. In combination with a blade or vane holding element, an annular row of blades or vanes provided with substantially aligned holes near their outer or free ends, a spacing piece between individual blades or vanes, provided at either end with lugs which extend into said holder.

10. In combination with a blade or vane holding element, an annular row of blades or vanes provided with substantially aligned holes near their outer or free ends, and a spacing piece, a portion of which lies between adjacent blades and portions of which extend into the holes in said blades.

11. In combination with a blade or vane 130

holding element, an annular row of blades, a spacing piece between adjacent blades, and means, formed integrally therewith, for securing said piece in place.

5 12. In combination with a blade or vane holding element, an annular row of blades or vanes, and a spacing member for the outer or free ends of the said blades or vanes, a portion of which lies between adjacent blades 10 or vanes and a portion of which is secured to said blades to hold said element in place.

13. In combination with a blade or vane holding element, an annular row of perforated blades, spacing pieces between adjacent blades and means coöperating with said perforations for holding said pieces in place.

14. In combination with a blade or vane holding element, an annular row of blades having holes extending therethrough near one 20 end thereof, separate spacing pieces lying between adjacent blades and means coöperating with the holes in said blades for securing said pieces in place.

15. In combination with a blade or vane holding element, an annular row of perforated blades or vanes, separate spacing

members located between adjacent blades or vanes and means located centrally of said spacing members and extending into the perforations of said blades or vanes for locking said spacing members to said blades or vanes. 30

16. In combination with a blade or vane holding element, an annular row of blades or vanes secured to said element and separate 35 spacing members located between adjacent blades or vanes adjacent to their outer or free ends.

17. In combination with a turbine blade or vane holding element, an annular row of 40 blades or vanes, individual spacing members located between adjacent blades or vanes and means for locking said spacing members to said blades or vanes.

In testimony whereof, I have hereunto 45 subscribed my name this eighteenth day of April, 1905.

RAYMOND N. EHRHART.
